RADIATOR CORE

Philmore F. Sperry, Chicago, Ill., assignor to Excel Auto Radiator Company, Chicago, Ill., a corporation of Delaware

Application July 21, 1930, Serial No. 469,429

Filed July 21, 1930, and Patented Aug. 14, 1934.

1. Claim. (Cl. 257—130) A radiator core for an internal combustion motor, comprising a strip of metal having a series of corrugations of different sizes and a series of bends, the bends being disposed in a staggered relation, and the openings between the bends being located between the opposed bends for the passage of air in a transverse direction, and with or without protuberances opposite such openings for deflecting the air passing therethrough.

Another object of the invention is to provide such a device without narrowing the width of the strip or sheet of metal from which the division plate or spacer is fashioned. This may be accomplished by shearing the plate at points where the bends of a series of corrugations extend in an opposite direction to adjacent bends of adjacent series of corrugations.

This avoids the drawing of the metal between such bends and the consequent narrowing of the metal strip or sheet. Also, by so shearing the sheet or strip at the points stated, openings occur between the oppositely directed adjacent bends. In this way, the core may be made from the same strips of metal all having the same widths, in lieu of using strips of one width for the water walls, and of another width for the air spacer.

In a specific embodiment illustrative of the invention, the spacer is made from a strip or ribbon of sheet metal, and is formed at each of its opposite borders or margins, with a series of relatively large corrugations or zigzag formation, and along the middle of the strip is provided a series of protuberances alternately projecting in opposite directions, and with the protuberances on each side located in transverse alignment with the bends of the border corrugations. Intermediate between the border corrugations and the protuberances, are series of smaller corrugations, such as about one-half or one-third of the size of the border corrugations and about twice or thrice in number. Alternate bends of these smaller corrugations, such as each second or third bend on a side, are disposed also in transverse alignment of the bends of the larger corrugations, but extending in an opposite direction. This is effected by shearing the sheet metal at such intervals at the inner edges of the bends of the larger corrugations. This prevents a narrowing of the sheet or strip, and also provides for openings between the larger bends and the adjacent or corresponding smaller bends of these corruga-

tions. By disposing the protuberances opposite these openings, the air passing through such openings will be deflected by such protuberances.

By also making the smaller corrugations with smaller altitudes than of the larger corrugations, channels are provided along each side of the line of the smaller corrugations, and between the protuberances and the border corrugations, whereby flow of air along these channels may be attained in addition to the streams passing transversely between the protuberances. The protuberances are also designed to engage the adjacent side walls of the water passages on each side of the air passage.

Other objects, advantages, capabilities, features and process steps are comprehended by the invention as will later appear and as are inherently possessed thereby.

Referring to the drawing, Fig. 1 is a fragmentary elevational view of a core constructed in accordance with the invention.

Fig. 2 is a sectional view taken in a plane represented by line 2—2 in Fig. 3 of the drawing; Fig. 3 is a transverse sectional view taken in a plane represented by line 3—3 in Fig. 2 of the drawing; and

Fig. 4 is a plan view of a fragment of a division plate or spacer constructed in accordance with the invention.

Referring more in detail to the drawing, the embodiment selected to illustrate the invention is shown in connection with a radiator core made up of sections between which are provided tortuous water passages or channels 1. Each section comprises corrugated side walls, 2 and 3, between which the water passes from one end to the other end of the core. The ends of the walls 2 and 3 are suitably connected together by joints such as lap-joints 4. At the margins of the walls 2 and 3 are provided flared or belled portions 5, 6, 7 and 8 with the flanges 5 and 7 of the walls 2 and 3 fitting together on one side of the core and the flanges 6 and 8 of these walls fitting together on the other side of the core and all soldered together to seal the water channels.

The walls 3 and 2 of a section encloses between them a transverse air passage 9. Within this air passage may be located the division plate or spacer above mentioned and shown in detail in Fig. 4 of the drawing.

This spacer comprises series of large corrugations 10 and 11 at the borders or margins of the spacer strip. Along the middle of this strip is also provided a series of protuberances 12 and 13

having flat tops or apexes, such that the protuberances 12 extend or project from one side of the plate and the alternate protuberances 13 extend or project from the other or opposite side 5 of the plate. Each protuberance has at its side inclined walls 14 and 15 disposed in line with the bends 10 and 11 of the marginal corrugations.

Intermediate the protuberances and the marginal corrugations are disposed series of smaller corrugations 16 and 17. These corrugations are of smaller size and altitude than those of the border corrugations. In forming these corrugations the sheet metal is sheared at points 18 and 19 to form slits such that the bends 10 and 11 of the large corrugations will extend in one direction while the bends 16 and 17 of the smaller corrugations will extend in the opposite direction and thus provide openings or holes 20 and 20' for the transverse passage of air toward the protuberances. The smaller corrugations will also provide two other bends 21 or 22 between each of the bends 16 or 17, one side of each bend also being a side of the bend 17 or 16 on the opposite side of the plate.

25 The protuberances may be provided with depressions 23 adapted to register with projections 24 formed in the water walls 2 and 3 for the purpose of positioning the spacer plates in the air passage in proper relation with the water walls and also to aid in maintaining this relation between them.

It will be noted that the protuberances engage in staggered relation with the opposite walls of the water passages in supporting and bracing relation. The result and effect of the corrugated forms of the spacers and the water walls is to give the radiator a honey-comb appearance.

In assembly the sections are placed together with the belled parts 5, 6, 7 and 8 in engagement and the air spacers in position with the projections 23 and 24 registering, and then the aggregate is dipped in molten solder to unite the belled parts.

In the assembled core, the cooling water passes
45 through the heat exchanger and enters the steam
coil in the top of the reactor and is then returned to the
bottom of the reactor. The cooling water passes
through the heat exchanger and enters the steam
coil in the top of the reactor and is then returned to the
bottom of the reactor. The cooling water passes
50 through the heat exchanger and enters the steam
coil in the top of the reactor and is then returned to the
bottom of the reactor. The cooling water passes
through the heat exchanger and enters the steam
coil in the top of the reactor and is then returned to the
bottom of the reactor. The cooling water passes
55 through the heat exchanger and enters the steam
coil in the top of the reactor and is then returned to the
bottom of the reactor. The cooling water passes
through the heat exchanger and enters the steam
coil in the top of the reactor and is then returned to the
bottom of the reactor. The cooling water passes
60 through the heat exchanger and enters the steam
coil in the top of the reactor and is then returned to the
bottom of the reactor. The cooling water passes
65 through the heat exchanger and enters the steam
coil in the top of the reactor and is then returned to the
bottom of the reactor. The cooling water passes
70 through the heat exchanger and enters the steam
coil in the top of the reactor and is then returned to the
bottom of the reactor. The cooling water passes
75 through the heat exchanger and enters the steam
coil in the top of the reactor and is then returned to the
bottom of the reactor. The cooling water passes

through the tortuous passage 1 and the air passes transversely through the air passages 9, part of the air stream passing through the openings 20 and 20' and against the inclined surfaces 14 and 15 of the protuberances so as to cause the air stream to be deflected and pass on both sides of each protuberance, and some of the air may pass even over the small corrugations in the channel between the protuberances and the border corrugations.

While I have herein described and upon the drawing shown an illustrative embodiment of the invention, it is to be understood that the latter is not limited thereto but may comprehend other constructions, arrangements of parts, details and features without departing from the spirit thereof.

Having thus disclosed the invention, I claim:

In a radiator core having liquid passages and intermediate air passages, said liquid passages being of zig-zag shape, each bend thereof having the inner side bent sharply and the outer side flat, a division plate between said liquid passages and forming said air passages between it and said liquid passages, said plate having a border of zig-zag shape, the bends of said border contacting the bends of said liquid passages, the part adjacent said border being of zig-zag shape, the bends thereof being smaller in size than the border bends and certain of said smaller bends extending in the opposite direction to and being in line with the larger bends, said opposed bends being so arranged and constructed as to provide air passages therebetween, the center portion of said plate being also of zig-zag shape, the apex and ends thereof being flat, the apex contacting the flat bends of the water passages and the ends sloping down therefrom and into the adjacent smaller bends to form a barrier for each air passage and to deflect substantially all the air passing therethrough against the sides of the water passages.
